United States Patent Office

Des. 202,940
Patented Nov. 16, 1965

202,940

FILE FOLDER

Roy M. Bloom, 13 Harcourt Road, Scarsdale, N.Y.

Filed Nov. 17, 1964, Ser. No. 82,654

Term of patent 14 years

(Cl. D59—2)

FIG. 1 is a front elevational view of a file folder showing my new design;

FIG. 2 is a top plan view thereof;

FIG. 3 is a sectional view taken on the line 3—3; and

FIG. 4 is a sectional view taken on the line 4—4.

I claim:

The ornamental design for a file folder, as shown.
